Primary Examiner — Susan Bennett Hattan*Assistant Examiner* — Marie Fast Horse(74) *Attorney, Agent, or Firm* — Arent Fox LLP(57) **CLAIM**

The ornamental design for a tray, as shown and described.

DESCRIPTION

FIG. 1 is a perspective view of a tray showing our new design; FIG. 2 is a front view of the design shown in FIG. 1; FIG. 3 is a rear view of the design shown in FIG. 1; FIG. 4 is a top view of the design shown in FIG. 1, wherein the bottom view is identical to the view in FIG. 4; FIG. 5 is a right side view of the design shown in FIG. 1, wherein the left side view is identical to the view in FIG. 5; FIG. 6 is a perspective view of a second embodiment of a tray showing our new design; FIG. 7 is a front view of the design shown in FIG. 6; FIG. 8 is a rear view of the design shown in FIG. 6; FIG. 9 is a top view of the design shown in FIG. 6, wherein the bottom view is identical to the view in FIG. 9; and, FIG. 10 is a right side view of the design shown in FIG. 6, wherein the left side view is identical to the view in FIG. 10. The broken lines shown in the drawings represent unclaimed portions of the tray and form no part of the claimed design.

1 Claim, 8 Drawing Sheets(56)
